UNITED STATES PATENT OFFICE

2,520,661

CRUCIFIX

Percy Charles Stanley, East Orange, N. J.

Application December 3, 1947, Serial No. 789,518

1 Claim. (Cl. 206—19)

1

This invention relates to a crucifix and a mounting therefor.

A prime object of the present invention is to provide a crucifix with improved means for mounting or supporting it in an upright position on a horizontal support such as a table or the like.

Another object is to provide a crucifix suitable for storing religious articles such as used in the rites of the Christian religion.

A specific object is to provide a crucifix with a removable base that is adapted to be detachably supported in compact arrangement on the rear of the crucifix when not in use.

A further object is to provide a crucifix with removable parts that are easy to assemble and disassemble.

Still another object is to provide a crucifix that is simple in construction, inexpensive to manufacture and dignified in appearance.

Other objects and advantages of the invention will be apparent from the description thereof to follow taken in connection with the accompanying drawings in which:

Figure 1 is a perspective view of a crucifix embodying my invention mounted on its base or support.

Figure 2 is a rear elevational view thereof with the base in collapsed position.

Figure 3 is a side elevational view of the device shown in Figure 2.

Figure 4 is a cross-sectional view taken on the plane of the line 4—4 of Figure 2.

Figure 5 is a cross-sectional view taken on the plane of the line 5—5 of Figure 2, on an enlarged scale.

Figure 6 is a cross-sectional view taken on the plane of the line 6—6 of Figure 2, on an enlarged scale.

Figure 7 is a cross-sectional view taken on the plane of the line 7—7 of Figure 2, on an enlarged scale.

Figure 8 is a fragmentary vertical central sectional view of the lower end of the crucifix and its base on an enlarged scale.

Figure 9 is a perspective view of the detachable base.

Figure 10 is a perspective view of the rear cover plate.

Referring to the drawings, the crucifix comprises an upright or vertical member 1 and a horizontal member 2, both formed of wood. The members are grooved at their meeting surfaces to form a joint 3 where they are cemented or otherwise secured together to make a cruciform body.

The vertical member 1 is formed with a cut-out 55 end of the cover plate 6.

2

portion extending from a point adjacent its juncture with member 2 to a point remote from its bottom end 4 thus forming a compartment 5 open at its rear. The rear opening in the compartment 5 is closed by a removable plate 6 which is adapted to slide in grooves 7 in the side walls 8 of the compartment and is adapted to seat in a groove 9 formed in the lower wall of the compartment adjacent its rear surface. The grooves 7 have open ends adjacent the lower edge of the horizontal member 2 and the cover plate when in compartment-closing position has its upper edge disposed at said lower edge of the horizontal member as best shown in Figures 2 and 5. The upper end of the plate overlaps the bottom edge of the upper wall of the compartment. Plate 6 may be made of plastic or other suitable material.

The compartment 5 may of course be used for storage of such articles as are used in the rites 20 of the Christian religion particularly those used by the clergy of the Roman Catholic Church in administering the last sacrament. In Figure 2 for example, candles 10 and a bottle 11 of holy water are shown stored in the compartment. 25 These articles may be held in orderly fashion in the compartment by brackets or lugs (not shown) of any suitable kind.

Detachably mounted on the rear surface of the upper end of vertical member 1 and on the rear 30 surface of the horizontal member 2 is a T-shaped plate 12 formed of wood, plastic material or any other desirable material. The plate 12 has a horizontal section or cross piece 13 corresponding in size and shape to the horizontal member 2, 35 and a stem or vertical portion 15 corresponding to the upper portion of the vertical member 1 above said horizontal member. Projecting from the opposite ends of the horizontal section 13 of the plate is a pair of cylindrical candle sockets or 40 holders 14 which may be formed separately from the plate and suitably fastened thereto or may be formed integrally therewith. On the upper free end of the vertical section 15 of the plate 12 is a projecting stud member 16 which may be made 45 separately from or integrally with the plate as described.

Plate 12 is frictionally held in position on the rear of the crucifix by the stud member 16 slidably fitting in a recess 17 in the upper end of the 50 vertical member 1 and opening to its rear surface, and by the candle sockets 14 slidably fitting in recesses 18 formed in the opposite ends of the horizontal member 2. When in this position, the plate overhangs and protects the upper

When it is desired to use the crucifix for administering the last sacrament of the Church, for example, the crucifix is supported in an upright position such as shown in Figures 1 and 8 on a horizontal support such as a table or the like. For this purpose, the T-shaped plate 12 is removed from its position at the rear of the crucifix by sliding the stud and candle sockets out of their respective recesses. When so detached, the plate may be used as a base for the crucifix by inserting the stud member 16 into a central recess 19 in the lower end of the vertical member 1 as shown in Figure 8. This positions the cross piece 13 in front of the crucifix to support it in upright position and places the candle sockets or holders 14 in proper position for receiving the candles 16. When the base plate 12 is removed from its position above the cover plate 6, said cover plate can readily be slid upwardly and removed in order to permit removal of the 20 articles in the compartment 5.

Changes in details might be made without departing from the principle of the invention.

What I claim is:

A crucifix comprising a cruciform body including a vertical member and a horizontal member of substantial thickness, said vertical member having a compartment in the lower portion of its rear side, guide grooves in the walls of said compartment and open at one end adjacent the 25 lower edge of said horizontal member, a cover plate for said compartment slidably mounted in said guide grooves with one end disposed at the

5 lower edge of said horizontal arm when the cover plate is in compartment-closing position, a thin T-shaped plate including a stem portion corresponding in size and shape to the upper portion of said vertical member and a cross piece corresponding in size and shape to said horizontal manner, said T-shaped plate having a stud on its stem portion and also having candle sockets adjacent the ends of its cross piece, the upper portion of said vertical member and the end portions of said horizontal member at the rear sides of the cruciform body having sockets to frictionally and separately receive said stud and said candle sockets respectively for separably connecting said T-shaped plate to said cruciform body with its cross piece in abutting relation to said end of said cover plate and holding the cover plate in compartment-closing position, the lower end of said vertical member having a socket to frictionally receive said stud on said T-shaped plate for connecting said T-shaped plate to said vertical member at right angles thereto to support said cruciform body in upright position.

PERCY CHARLES STANLEY.
